SIGNAL

John F. Kepler, Chicago, Ill.

Application December 31, 1940, Serial No. 372,587

2 Claims. (Cl. 177—327)

This invention has to do with traffic control signalling apparatus. More particularly it relates to an improved signal together with control means whereby traffic as that upon city streets or upon highways is signalled to stop and go and is given an exact indication of when the signal will change.

An object of the present invention is the provision of a new traffic signal wherein there are a plurality of visual signal issuing portions which are caused to manifest their signals of respective traffic conditions in predetermined sequence, and wherein there is also means for gradually diminishing the manifesting area of such signal issuing portions during signal manifestation as a simple expedient of informing an observer how much of the signal period remains.

Another object of this invention is the provision of a traffic signal device having an opaque mask or shield gradually movable across a signal lens to diminish the visible illuminated area thereof whereby an observer can accurately ascertain when the lens will become completely blanked simultaneously with termination of the traffic condition period to which it pertains.

Another object of this invention is the provision, in a traffic signal device, of a signal dial in which there are sequentially energized signal issuing sections arranged circumferentially about the dial face and a shield pivoted at the dial center to enable it to sweep across and thus gradually cover each section while it is energized.

Another object of the invention is the provision of a novel traffic signal device according to the next preceding object and wherein there is means for energizing and deenergizing the signal issuing sections in synchronism with the shield movement whereby each section is energized as the shield starts to sweep thereacross and is deenergized following complete coverage by the shield.

A further object is the provision in traffic signalling apparatus of a composite signal issuing dial in which there is a novel arrangement of dial sections respectively pertaining to "stop" and "go" for vehicular traffic and "walk" for pedestrian traffic.

Another object is the provision, in a traffic regulation system, of a camera placed under control of an electric circuit energized jointly by a vehicle actuated circuit closing means and a circuit closing means which is enabled only during energization of the "stop" section of the traffic signal apparatus, whereby a vehicle will be photographed while passing contrary to a stop signal.

Another object is the provision of traffic signalling apparatus as recited in the foregoing object, embodying means for energizing subject il-

luminating means simultaneously with operation of the camera.

Another object is the provision of traffic control apparatus as the above in which electrically controlled means is present for conditioning the camera for a succeeding exposure and likewise for conditioning the subject illuminating means preparatory to functioning simultaneously with a succeeding photographic operation.

A further object is the provision of a warning sound signal in circuit with the aforesaid jointly energized circuit to audibly notify a vehicle operator when he drives in violation of a stop signal.

A further object is the provision of a new shield member movable across and into registration with a signal light.

A still further object is the provision of an improved road bed switch having delayed action so that a single picture will be taken of a vehicle passing over the same with continuous movement but whereby a second picture will be taken, when the back wheels of the vehicle operate the switch, in the event the vehicle comes to rest with the switch between the front and back wheels while the stop signal is operating.

These and other desirable objects inherent to and encompassed by this invention will later appear.

In the drawings:

Fig. 1 is a front elevational view of a traffic signal device constructed according to the principles of the invention;

Fig. 2 is a sectional view taken substantially upon the line 2—2 of Fig. 1;

Fig. 3 is a vertical sectional view taken forwardly substantially upon the line 3—3 of Fig. 2;

Fig. 4 is a wiring diagram of the device and control circuits;

Fig. 5 is a perspective view of a street intersection illustrating a typical installation of the devices; and

Fig. 6 is an elevational view of a modified form of light shield for the device.

With the exception of certain control circuits and a road bed switch for closing the same, all subsequently described herein, the apparatus is enclosed by a housing 10 supported as upon a standard 11, Figs. 1 and 5, in any customary manner. For instance, the housing 10 may be suspended at any desired position over a street or street intersection by supporting means such as cross arms or cables.

The embodiment herein illustrated, to expedite a clear comprehension of the invention, has but a single viewing or signal face, referred to as the front face, although it will be understood that any additional number of faces may be provided with signal indicating means.

Referring now to Figs. 1, 2 and 3, the housing

19 which is substantially square in horizontal section has a front wall 12 and an upright corner frame member 13 at each of its back corners, one of these corner members being shown in Fig. 2. The back wall and the two side walls are open, the back wall opening 14 being normally closed by a door 15 secured to one of the frame members 13 by hinges 16, whereas the left wall opening 17, Fig. 3, is closed by a door 18 upon hinges 19, and the right wall opening 20 is closed by a door 21 mounted upon hinges 22. The stationary part of the hinges 19 and 22 are attached to opposite edges of the front wall 12. A generally arcuate top wall 23 covers the housing.

A circular indicator face or dial 24 comprising segmental indicator sections 25, 26, 27 and 28 is mounted in the front wall 12. These sections respectively bear the words "Stop," "Walk," "Go" and "Walk" and include translucent sheets or lenses of such material as colored glass upon which said words appear. According to conventional practice the translucent material bearing the word "Stop" will be colored red so that when a light is flashed behind it this section of the signal face 24 will issue a red light to an observer. The translucent material bearing the word "Go" will be stained or colored green so that when a light is flashed behind it this section of the face 24 will appear green to the observer. Sections 26 and 28 preferably appear white to the observer so that the sheets of translucent material upon which the words "Walk" appear will be frosted or otherwise suitably processed to give the desired effect. Means, presently to be described, is employed in the device for periodically and successively energizing the sections 25, 26, 27 and 28 in rotation, and, while this order of rotation may be either clockwise or counter-clockwise, I prefer to cause their energization in the clockwise order as viewed in Fig. 1 wherefore following energization of the section 25, section 26 will be energized, then section 27, then section 28, then section 25, and so on. Each section is deenergized substantially coincident with energization of the next.

I employ in conjunction with the signal sections as 25 a sector-like shield member 29 which is carried upon and rotated clockwise by a shaft 30. This shield member 29 extends circumferentially about the dial 24 a distance at least as great as the circumferential distance of the sections 25 and 27 to enable it to completely mask any of the dial sections. Said shaft 30 and the shield 29 are rotated clockwise by means presently to be described, and in synchronism with the means for causing energization or illumination of the dial indicating sections as 25. Such synchronization between the rotation of the shield 29 and energization of the dial indicating sections is such that each of the sections as 25 will be energized simultaneously with the leading edge 31 of the shield arriving at the approach edge as 32 of said sections. Energization of each section as 25 continues while the leading edge 31 of the shield advances thereover, the traffic condition designated by the particular dial section continuing so long as any part remains uncovered by the shield. Although this condition of the traffic will terminate simultaneously with complete coverage or masking of the dial section, an observer in traffic will be able to accurately estimate the termination or change in traffic condition by observing the size of the uncovered energized sector and the rate at which its area is being diminished.

When the shield 29 completely covers a dial section, that section is deenergized and the next section is energized, the shield continuing in its movement and gradually covering the newly energized section, and so on about the dial, each dial section being energized by illumination and immediately being slowly traversed by the shield so that an observer can accurately determine when the traffic condition indicated by that particular section will terminate.

The shield 29 carries adjacently to the juncture of its leading edge 31 and its outer arcuate edge 33 an electric light bulb 34 visible through a small opening 35 in a casing 36 and in current carrying relation with a socket portion 37 to which electric energy is supplied through a conductor pair within a cable 38. The manner in which electric energy is impressed upon the conductors in the cables 38 will be described presently, although it is pointed out at this time that the indicator bulb 34 is lighted at all times during operation of the device to assist pedestrians and vehicle operators in gauging the position of the leading edge 31 upon the shield member 29. A hoop-like strip 39 attached to the shield 29 in spaced relation from its edge reinforces the same and also prevents the passage of light rays from the indicator lamp 34 onto the dial 24.

In the upper part of the housing 10 I provide a camera 40 shown in dotted outline in Fig. 1. The objective lens 41 of the camera projects outwardly through an opening 42a in the housing front wall 12. An electromagnet 42 for controlling said camera is energizable pursuant to the closing of a roadway switch 43 of which a bar-like actuator member 44 is shown in Fig. 5. Circuit closing means, later to be described and operating synchronously with the energizing means for the dial sections as 25, must be conditioned concurrently with actuation of the switch bar 44 to enable such actuation to energize the electromagnet 42, and said circuit closing means is conditioned only while the "stop" section 25 is energized. Therefore vehicles may pass over the bar 44 without energizing the electromagnet 42 excepting during energization of said "stop" section. The energized electromagnet 42 manipulates the camera shutter to cause a picture to be taken wherefore a vehicle passing over the bar 44 while the "stop" section is energized will be photographed. Said electromagnet 42 further controls the flashing of the one of several photo-flash bulbs 45 carried in a rotatable frame 46 that is in registry with an opening 47 in the casing front wall, concurrently with the exposure period of the camera shutter, so that adequate illumination will be had of the photographed subject. Means all fully described hereinafter is operable by the electromagnet 42 for rotating the frame 46 for placing a new bulb 45 in registry with the opening 47 after the taking of each picture, and also for winding the film advancing mechanism of the camera and re-cocking the camera shutter.

Means in the form of a siren, horn, bell or other auxiliary signal device, indicated generally at 48 is also controlled by the electromagnet 42 so that the vehicle operator who has run through the red light and therefore operated the switch bar 44 will be warned of his traffic violation.

Referring now to Figs. 1, 2 and 3, the front wall 12 is shown to have a circular opening 49 through which the dial 24 is visible. Said opening 49 is provided with a sun shade member 50 of conventional design. The visible-signal indicat-

ing part of the device comprises a casing 51 of which the bottom wall BW is substantially square and has at its corners four short legs which are fastened to the standard 11 by machine screws M. The front and back walls 52 and 53 of the casing 51 are also substantially square wherefore there are two opposite vertical side walls 53a and 53b and a horizontal top wall 53c. A cover plate constitutes the back wall 53. Said front wall includes the dial 24 which shows through the housing opening 49 and a circular flange 53d projects forwardly from about said dial into close fitting relation with the edge of the opening 49. The entire casing including the dial 24 may be withdrawn from the housing 10 for inspection or repair after removal of the screws M. Said casing 51 is divided internally by a plurality of radially disposed partition walls 55, 56, 57 and 58, which coincide with the dividing lines between the signal sections 25, 26, 27 and 28. These partition walls as 55 together with the dial sectors disposed therebetween and the portions of the back wall 53 behind such dial sectors form compartments from which light cannot escape. Incandescent light bulbs 59, 60, 61 and 62 are disposed respectively in said compartments. Lamp sockets 63 of any conventional type are mounted upon the rear wall 53, said sockets projecting inwardly through wall openings 64 and being attached to small cover plates 65 for such openings. Means as screws 66 may be employed for holding the sockets 63 and the plates 65 in position. Each of the sockets 63 has a pair of conductors as 67 and 68 connected therewith for supplying electric energy to its associated bulb as 62.

The aforementioned shaft 30 which carries the light shield member 29 upon its front end is suitably journaled upon bearing members 69 and 70 respectively at the center of the dial 24 and in a central portion of the rear wall 53. Said shaft 30 is hollow and thus receives a section of the cable 38 for supplying electrical energy to the indicator light 34, Fig. 1. A pair of slip rings 71 and 72 are carried upon the shaft 30 by insulator rings 73 and 74 and connection is made respectively with these slip rings by conductors 75 and 76 of the cable 38 which pass outwardly of the shaft 30 through apertures 77 and 78. Electric energy is fed to the slip rings 71 and 72 through brushes 79 and 80 which are mounted upon an insulator block 81 suitably attached to the casing rear wall 53.

The shaft 30 is driven from a speed reducing mechanism 22 which in turn is driven by an electric motor 83. That section of the shaft 30 between the casing rear wall 53 and the speed reducer 22 carries an electrical conductor slip ring 84 suitably insulated from said shaft by a flanged sleeve 85. The electric energy supplied to the slip ring 84 by a brush 86 carried upon an insulator support 87 is impressed upon a rotary distributor arm 88 having an end section which has contact with a distributor disk 89 that is fixed to the casing rear wall 53. This disk 89 comprises a body 90 of insulating material in which there is set four commutator segments 91, 92, 93 and 94, insulated from one another and from the casing 51 by the insulator disk 90. A central opening 95 in the distributor member 89 is oversize with respect to the shaft 30 wherefore the latter makes no electrical contact with any of the commutator segments as 91.

In Fig. 4 where the parts thus far described are shown schematically, the electric motor 83 is

connected to circuit conductors 96 and 97 by lateral conductors 98 and 99. A switch such as a double-pole single-throw switch 100 may be employed for connecting the circuit conductors 96 and 97 with an electric energy supply line comprising conductors 101 and 102. Upon the closing of said switch 100 the motor 83 will begin rotation and drive (at predetermined uniform speed) the speed reducing unit 22 which has a mechanical driving connection, represented by the dot-dash line 104, with the slip ring 84, with the slip rings 71 and 72 and with the dial shield 29. That is, the mechanical connection comprising the shaft 30 and represented by the dot-dash line 104 in Fig. 4 causes the slip ring 84 and the distributor arm 88 to rotate in timed relation with the dial shield 29. The brush 86 which supplies electric energy to the ring 84 and to the distributor arm 88 is connected with the circuit conductor 97 through a conductor 105 so that as the distributor arm 88 rotates clockwise in the direction indicated by the arrow in Fig. 4 the electric energy of the polarity corresponding to the conductor 97 will first be fed to the segment 91, then to the segment 94, then to the segment 93 and then to the segment 92 and so on. While the arm 88 is in engagement with the sector 91, a circuit will be completed through the conductor 67, the light bulb 62, conductor 68 and a common conductor 106 back to the line 96 of opposite polarity, causing energization of the bulb 62 and hence the section 27 of the indicator dial. In Fig. 4 it is illustrated that the distributor arm 88 bears the same relation in terms of rotative position with respect to the segments as 91 as does the leading edge 31 of the shield 29 with respect to the dial sections as 27. It will be seen therefore that when the distributor arm 88 first made contact with the commutator segment 91 the leading edge 31 of said shield reached registration with the approach edge 107 of the "go" dial sector 27, and that at the time the leading edge of the shield has completely traversed said dial sector to obscure the manifesting character thereof the distributing arm will pass from engagement with the commutator segment 91 to break the energization circuit for the bulb 62 wherefore this dial sector will become deenergized or non-illuminated. Substantially simultaneously, however, the distributor arm 88 will engage the commutator segment 94 to complete a circuit from the conductor 97 through the brush 86, the slip ring 84, the distributor arm 88, a conductor 108, the bulb 59, a conductor 109 and the common conductor 106 to the opposite side of the circuit, causing energization of the bulb 59 and the "walk" dial sector 28. As the leading edge 31 of the shield 29 traverses the dial sector 28, the distributor arm will likewise be traversing the commutator segment 94 so that at the time the dial sector 28 is completely covered by the shield the distributor arm will break contact with the sector 94 to deenergize the bulb 59. Next, the distributor arm will engage the commutator segment 93 to complete a circuit through a conductor 109, the bulb 60, a conductor 110 and the common conductor 106 for energizing said bulb 60. Eventually the distributor arm 88 will contact the commutator sector 92 to complete a circuit through a conductor 111, the bulb 61, a conductor 112 and the common conductor 106 for energizing said bulb 61.

So long as the switch 100 remains closed, the motor 83 will drive the speed reducing unit 22,

the distributor arm 88 and the dial shield member 29 to cause the indicating sections of said dial to be successively energized and the dial shield to slowly traverse and thus diminish the effective manifesting area of each energized section. The conductors at 96 and 97 are connected directly with the brushes 79 and 80 which engage the slip ring 71 and 72 for supplying electrical energy through the conductors 75 and 76 to the indicating lamp or bulb 34 upon the shield 29.

The electromagnetic device 42 for controlling the siren and the camera mechanism includes a casing 120 mounted upon and suitably secured to the upper wall 53c of the casing 51. A solenoid 121 of the device 42 contains an axially movable armature 122 which is held in the position shown in Fig. 2 by means of a spring 123 when said solenoid is not energized. One end of the spring 123 is connected with a fixed pin 124 while the opposite end thereof is connected with a stud 125 depending from the armature 122. When the electromagnet 42 is energized by passing an electric current through the solenoid 121 by means presently to be described, the armature 122 will be acted upon by the resulting magnetic field and thus be moved endwise to the left in Fig. 2.

The right end of the armature 122 is bifurcated and thus receives the lower end of an arm 126 of which a hub 127 is fixed to a shaft 128 having opposite ends journaled within brackets or plates 129 and 130 secured to the casing upper wall 53c. Also fixed to the shaft 128 is an arm 131 for tripping an actuating pin 132 for the camera shutter. Another arm, 133, fixed to the shaft 128 as shown in Fig. 3, is pivotally connected with an arm 134 which has in its back end a slot 135 receiving a pin 136 projecting endwise and eccentrically from a film winding and shutter cocking knob 137 of the camera. Still another arm, 138, fixed to the shaft 128, is pivotally connected with a pawl arm 139 which cooperates with a ratchet wheel 140 for advancing the bulb carrier 46 one step after each camera exposure. The connection between the arm 138 and the pawl arm 139 consists of a small bracket 141 suitably secured to the arm 138 and a pivot pin 142 mutually within the bracket and the lower end of the pawl arm. A spring 143 having an end anchored to a bracket 144 depending from the top of the housing 10 yieldingly holds the pawl lever to the left, Fig. 3, with a bearing surface 145 against a tooth of the ratchet wheel 140.

Said bracket 144 has a flange 146 that is secured to the upper housing wall by any standard fastening means as machine screws 147. An opening in the bracket 144 is provided with a bearing sleeve 148 in which there is journaled a shaft 149 upon which the ratchet wheel 140 is fixed. The carrier 46 is rotatively fixed to the front end of the shaft 149 and is insulated therefrom by an insulator bushing 150. Said carrier is made of pressed steel or other electrical conductor material and it has a backwardly turned flange 151 which serves as a slip ring to receive electric energy from a brush 152 carried by an insulator block 153 upon the bracket 144. An opening 154 in the bracket 144 accommodates an insulation covered conductor 155 which is electrically connected with the brush 152. A plurality of sockets 156 have their threaded side walls (not shown), for receiving the standard screw-threaded portion of the flash bulbs 45, electrically connected with the carrier 46. Insulating disks 157 respectively associated

with the sockets 156 carry electrical contacts 158 which are abutted by the end contacts (not shown) of the bulbs 45 when the latter are screwed home in their sockets 156. Near the bottom of the bracket 144 an electrical conductor stud 159 is provided, this stud extending through the bracket and being insulated therefrom by a sleeve 160. Each time the rotatable carrier 46 is advanced one of the contacts 158 will be stationed in registry and in electrical contact with the stud 159 so that upon the closing of an electric circuit including the conductor 155, the brush 152, the carrier 46, the filament of the bulb 45 in registry with the front wall 15 opening 47, the contact 158 associated with said bulb, the stud 159 and a conductor 161, said bulb will be energized for emitting light to the subject to be photographed. The just traced circuit, as will be seen in Figs. 4 and 2, includes a switch 162 having a switch actuating member 163 engageable by the stud 125 upon the electromagnet armature 122. The switch actuating member 163 includes an adjustable screw 164 to provide adjustment whereby the stud 125 will 25 close the aforesaid circuit for flashing a bulb 45 coincident with the opening period of the camera shutter.

The roadway switch 43 shown in Figs. 4 and 5 includes the aforesaid bar 44 which is supported upon compressible springs as 170, Fig. 4, substantially flush with the roadway surface. Also associated with the switch bar 44 is a dash pot of any conventional structure indicated generally at 171. Normally the springs 170 will hold the switch bar 44 upwardly whereby switch contacts 172 are open. While the traffic signal device is set for "stop," that is, with the dial section 25 energized wherefore the distributor arm 88 is engaged with the commutator segment 93, if an approaching vehicle should proceed in violation of the stop signal and thereby depress the switch bar 44, a circuit will be closed from the conductor 97 through conductor 105, brush 86, slip ring 84, distributor arm 88, segment 93, conductor 109, conductor 173, switch contacts 172, solenoid 121 of the electromagnet 42, and conductor 174 to the other side of the energy supply circuit. Consequently the electromagnet 42 would be energized, drawing its armature 122 to the left for operating the camera shutter-tripping arm 131 and for shifting the stud 125 into closing relation with the switch 162. Therefore the switch 162 will be closed while the camera shutter is open so that the circuit including the conductors 155 and 161, Figs. 2 and 4, and the flash bulb 45 in registry with the light tube 47 will be closed and said bulb energized for illuminating the vehicle as it advances beyond the roadway point determined by the position of the bar 44.

While the armature 122 was being drawn to the left, Fig. 2, for tripping the camera shutter and for closing the circuit which energized the flash bulb 45, the arm 138 caused movement of the pawl arm 139 upwardly while the cam surface 145 passed idly along and over the ratchet point P which the spring 143 causes it to yieldingly engage. A hook portion 146a upon the pawl arm is thus carried upwardly beyond said ratchet point P and drops into hooking relation therewith when the armature 122 reaches the left extremity of its movement. Upon deenergization of the electromagnet, the spring 123 returns said armature to its rightmost limit incident to rotating the shaft 128 and the arm 138 in the

direction for drawing the pawl arm 139 downwardly together with the point P which will then come to rest at the position shown as occupied by the point P'.

The points P of the ratchet wheel 140 are equal in number to the number of sockets 156 for the bulbs 45 and are correspondingly spaced about the carrier 46 so that each time the pawl arm 139 is actuated for advancing the ratchet wheel 140 the succeeding socket will be carried into registration with the contact 159, Fig. 2, preparatory to the bulb being lighted pursuant to a succeeding operation of the camera. Overthrow of the carrier 46 beyond the points at which the sockets 156 register with the contact 159 is prevented by a frictional break 161, Fig. 3, which is spring-pressed against the circular peripheral portion of the carrier.

When the electromagnet 42 is energized the link 134, connected with the shaft 128 through an arm 133, Figs. 2 and 3, will be moved rearwardly or to the left as viewed in Fig. 2 while sliding the slot 135 idly along the pin 136 in the camera reset knob 131. While the link 134 is in this rearward position the camera shutter is operated incident to which the knob 137 will spin counter-clockwise in the conventional manner, the pin 136 meanwhile moving idly backwardly in the slot 135. Later, when the spring 123 returns the armature 122 forwardly, the link 134 will be carried forwardly while the back end of the slot 135 acts upon the pin 136 for rotating the knob 137 to advance the camera film and to re-cock the camera shutter. It will be seen, therefore, that after the taking of each picture the spring 123 in returning the armature 122 to its forward position will cause a fresh bulb 145 to be moved into position for energization pursuant to the taking of a succeeding picture, and the camera reset knob 137 will be rotated for resetting the camera.

In Fig. 4 the mechanical connection between the armature 122 and the switch 126 is indicated by a dot-dash line 175; the mechanical connection between said armature and the ratchet wheel 140 is represented by a dot-dash line 176; the mechanical connection between said armature and the shutter trigger 132 is represented by the dot-dash line 177; and the mechanical connection between said armature and the camera reset knob 137 is represented by the dot-dash line 178.

The siren 48 has a motor section 155 and a cone 166, the former being connected with the housing upper wall 23 in any suitable manner. As will be seen in Fig. 4 the siren is connected in parallel with the electromagnet 42 by conductors 167 and 168 so that upon energization of said electromagnet by a vehicle depressing the switch bar 44 during energization of the stop section of the signal dial 24, as described above, the siren will be energized to audibly notify the vehicle operator of his traffic violation.

The dash pot 171, Fig. 4, will be so regulated that the switch bar 44 will remain downwardly to maintain the contacts 172 closed for a period sufficiently long for the back wheels of a vehicle in continuous movement to pass over the bar after it has been depressed by the front wheels. Thus a single picture will be taken of a vehicle passing over the bar 44 without stopping. Said dash pot may be so regulated that if the bar 44 should be depressed by the front wheels of a vehicle which then stopped with the bar between the front and back wheels, the bar would be re-

turned to the normal upward position prior to a change in the traffic signal whereby the back wheels would again depress the bar for causing a second picture to be taken when the vehicle proceeded in normal traffic. With the dash pot so regulated a single picture would be taken of a vehicle operated without regard to the stop signal while a second picture would be taken of a vehicle whose operator had stopped after becoming aware of his error.

It will be seen from the circuit diagram in Fig. 4 that the switch bar 44 may be operated for closing the switch contacts 172 without effect at times other than when the distributor arm 88 is engaging with the commutator segment 93 so that the vehicles may pass freely over said bar when to do so would not constitute a traffic violation.

In Fig. 5 the roadway switch 43 is shown operable in combination with a traffic signal device 10 both of which are for traffic advancing in the direction of the arrow 180 in the traffic lane in which a vehicle 181 is shown. There is also shown in dotted outline in Fig. 5, positions A, B and C where switches as 43 would be placed respectively for cooperation with signal devices placed upon roadway intersection corners A', B' and C'.

I have shown in Fig. 6 a modified form of shield 30 for cooperating with the signal dial 24. This shield which is designated 185 has a plurality of apertures 186 through which the energized section as 25 of the dial that is being covered thereby can be observed. These openings 186, enable 35 an observer to more easily ascertain the character of the traffic signal that is effective when the energized dial section becomes substantially covered.

It is thought that the invention and numerous 40 of its attendant advantages will be understood from the foregoing description and it is obvious that numerous changes may be made in the form, construction and arrangement of the several parts without departing from the spirit or scope of the invention, or sacrificing any of its attendant advantages, the form herein described being a preferred embodiment for the purpose of illustrating the invention.

The invention is hereby claimed as follows:

1. A traffic signal device comprising an indicator face including a plurality of portions significant of respective traffic conditions, means for successively illuminating said face portions to render them prominent in predetermined sequence, an opaque shield member having an advance edge, means for advancing said shield member, advance edge foremost, across and into light-shielding relation with each of said face portions during its illumination, and indicator light means disposed substantially coincident with said shield edge and advanceable with said shield member to assist an observer to ascertain the degree to which said face portions are shielded.

2. In a traffic signal device including a visible signal issuing section of substantial area, a shield member adapted for movement into registry with said section to indicate that the signal is no longer effective, and said shield member having a plurality of windows through which said area may be observed to facilitate ascertainment of the character of signal issued by such section.
